UNITED STATES PATENT OFFICE

EDGAR KENNETH HUNTER, OF LONDON, ENGLAND, ASSIGNOR, BY MESNE ASSIGNMENTS, TO KODAK LIMITED, OF LONDON, ENGLAND, AND INTERTYPE LIMITED, OF LONDON, ENGLAND

PHOTOGRAPHIC PRINTING PROCESS AND APPARATUS THEREFOR

Original application filed September 20, 1922, Serial No. 589,365, and in Great Britain September 21, 1921.
Divided and this application filed December 18, 1925. Serial No. 76,336.

An application for patent in Great Britain was filed on September 21, 1921.

The present invention relates to improvements in means for the preparation of printing plates or the like by the use of a photographic process of the type in which symbols, characters or the like to be printed are photographed singly and consecutively upon a sensitized surface, and constitutes a division 10 of my application Ser. No. 589,365, filed Sept. 20, 1922.

With the object of allowing any desired number of styles of character such as roman, arabic, italic and so forth, the characters of 15 each style, that is to say, the characters of each group or series are according to the present invention formed as light opaque stencils in series upon a flexible film so that it will be immediately seen that the number of available characters is almost unlimited as the flexible film can be of any desired length.

The invention is more particularly described with reference to the accompanying drawing showing diagrammatically one form 25 of character matrix or strip.

The character matrix of the present invention comprises a long strip 1 of celluloid or the like material having perforations 2 along its edges by means of which it can be displaced lengthwise and accurately positioned relatively to rows of characters 3, 4, 5, upon it.

The character strip 1 has a number of alphabets in sequence upon it as shown arranging with the individual characters normal to 35 the length of the strip and in rows one above the other, the arrangement being preferably such that the capitals, for instance, are in the upper row, the lower case in the second row, and the peculiars in the third row. The film strip contains characters along its length corresponding to a number of different styles, 40 such as modern, arabic, gothic, etc.

The film strip may have a portion 6 of its surface in which are punched perforations 7 in three groups corresponding to the groups 45 of characters 3, 4, 5, these punchings being adapted to operate pneumatically or electrically the operation of means for displacing a carriage bearing a light sensitive surface 50 by means corresponding to the body widths

of the characters spaced adjacent to them. The perforations 2 are preferably disposed most accurately relatively to the characters 3, 4, 5, so that they can be used as a mechanical means of bringing the characters with optical precision into any desired position. 55

I declare that what I claim is:—

1. As an article of manufacture a flexible film strip having a number of alphabets each of a different type arranged lengthwise in sequence thereon. 60

2. As an article of manufacture a flexible film strip having a number of alphabets each of a different type arranged lengthwise in sequence thereon, the individual characters being normal to the axial length of the strip. 65

3. As an article of manufacture a flexible film strip having a number of alphabets each of a different type in three rows comprising respectively the capitals, lower case and other characters, each arranged lengthwise in sequence thereon. 70

4. As an article of manufacture a flexible film strip having a number of alphabets each of a different type arranged lengthwise in sequence thereon, and mutilations on said strip for displacing or indexing the same. 75

5. As an article of manufacture a flexible film strip having a number of alphabets each of a different type arranged lengthwise in sequence thereon, and mutilations along the edges of said strip spaced accurately similar to the spacing of the individual characters thereon. 80

6. As an article of manufacture a flexible film strip having the characters of a number of alphabets arranged in sequence lengthwise thereon as light opaque stencils and groups of perforations in the strip varying differentially in number according to the body width 85 of the character to which they correspond and spaced similarly to the rows of characters. 90

7. As an article of manufacture a flexible film strip having the characters of a number of alphabets arranged in sequence lengthwise thereon as light opaque stencils and groups of perforations in the strip varying differentially in number according to the body width 95 of the character to which they correspond and spaced similarly to the rows of characters. 100

characters, and arranged in a portion of the film strip parallel with that portion carrying the characters.

8. As an article of manufacture, a flexible film strip having a plurality of light stencils 5 of symbols and characters arranged thereon, and punchings in the strip in predetermined positions for effecting the spacing of the sheet to be printed by values corresponding to the punchings, said punchings being positioned in 10 correspondence with the variable widths of letter spacing of the particular associated symbols.

In witness whereof, I have hereunto signed
my name this 4th day of December, 1925.

15 EDGAR KENNETH HUNTER.
